UNITED STATES PATENT OFFICE.

M. BURDETTE HAMMOND, OF BRIDGEPORT, ASSIGNOR TO I. NEWMAN & SONS, OF NEW HAVEN, CONNECTICUT.

BUSTLE.

SPECIFICATION forming part of Letters Patent No. 378,134, dated February 21, 1882.

Application filed December 7, 1881. Serial No. 237,186. (No model.)

To all whom it may concern:

Be it known that I, M. BURDETTE HAMMOND, a citizen of the United States, residing at Bridgeport, in the county of Fairfield and State of Connecticut, have invented certain new and useful Improvements in Bustles; and I do hereby declare the following to be a full, clear, and exact description of the invention, such as will enable others skilled in the art to which it appertains to make and use the same.

My invention relates to the manufacture of bustles, and has for its object to provide durable pivotal connections for the operative parts of the bustle.

My invention is adapted to all classes and styles of bustles, and is especially applicable to the various styles of bustles made from flat and twin wire. Heretofore in the manufacture of bustles the various parts have been connected together in a number of different ways, but principally by eyeleting and tying. Both of these modes of connection are open to serious objection. If cords are used, the connections are very bungling, considerable time and hand labor are required in attaching the bustle together, and the cords, moreover, are very apt to break in use. It has likewise been a serious objection to the use of eyelets, particularly in the case of twin-wire bustles, that they quickly tore out, rendering the bustles worthless. It has, moreover, been an important item of expense in the production of flat and twin-wire bustles that each piece of material must be provided at both ends with a metallic cap.

My present invention enables me to dispense entirely with the special metallic caps, the pivotal connections being so formed as to protect and conceal the ends of the strips.

With these ends in view I have devised the simple and novel construction of which the following description, in connection with the accompanying drawings, is a specification, numbers being used to denote the several parts.

Figure 1 is a side elevation of a bustle complete, showing the manner in which my invention is applied, the bustle being in the distended position; Fig. 2, a section on the line *x* *x* in Fig. 1; Fig. 3, a section on the line *y* *y* in Fig. 1; Figs. 4 and 5, elevations, full size, of the pivotal connections detached, Fig. 5 illus-

trating a special feature of construction when one of the parts of the connection is to be used at the end of a piece of flat or twin wire; and Fig. 6 is a partial side elevation of the bustle, showing the manner in which the pivotal connections act when the bustle is collapsed.

The bustle illustrated is substantially identical with the bustle described and claimed in my Patent No. 373,286, dated November 15, 1887.

1 denotes the belt; 2, the foundation-piece; 3, skirts connected to the belt and to which the foundation-piece is connected; 4, the ribs; 5, the stay-piece; 6, a supplemental rib connected to the stay-piece; 7, the connecting-strip, and 8 the returning-spring. These parts may all be of the usual or any preferred construction.

As already stated, the gist of my present invention lies in the novel manner in which the operative parts of the bustle are connected together.

9 and 10 denote clips, which are pivotally secured together in any suitable manner, as indicated in Figs. 3, 4, and 5. Ordinarily, a hole is punched in each clip and the two are secured together by an eyelet, 11, as clearly shown in Fig. 3. These clips consist simply of strips of metal, which are adapted to fold over the respective parts to which they are attached, as shown. When used with flat or twin covered wire, each of the clips is provided with lugs 12 upon its inner side, formed by punching in the metal, and with corrugations 13 at the edges, which may be formed by the cutting-dies. The object of these lugs and corrugations is to engage the textile covering of the wire, so that the clips will be held firmly in place by the mere act of closing them together and without additional means for fastening them. When the pivotal connection is to be used at the end of any of the parts—as, for example, at the ends of the ribs and the stay-piece—the base of the clip for the part whose end is to be covered is extended laterally and rolled up over the end of the rib or stay-piece, as at 14. (See especially Figs. 3 and 4.) This rolled end is an important feature in that it renders the use of metallic caps—such, for example, as are shown at the ends of the foundation-piece and the supple-

mental rib—wholly unnecessary where the clips are used. The attaching of the clips in place is so clearly illustrated as hardly to require explanation. For convenience, I have 5 designated the bases of the clips by 15 and the arms by 16.

It is sufficient to say that the pieces of wire and the clips are placed in proper position relatively to each other, and the arms of the clips 10 curved over the wires toward each other and then firmly pressed down, so that the lugs and corrugations upon the clips engage with the covering of the wire.

It will of course be understood that various 15 changes may be made in the details of construction without departing from the principles of my invention.

I claim—

1. A bustle consisting of foundation-piece,

ribs, connecting-strip, returning-spring, &c., 20 of ordinary construction, and clips 9 and 10, the bases of which are pivotally secured together and the arms of which embrace the respective parts to be joined together, and are provided with lugs and corrugations to engage 25 the ribs and hold them firmly.

2. A pivotal connection for the operative parts of bustles, consisting of a pair of clips pivoted together, each clip consisting of a base and arms, substantially as shown, one of said 30 bases having a lateral extension curved upward to cover the end of a rib or stay.

In testimony whereof I affix my signature in presence of two witnesses.

M. BURDETTE HAMMOND.
